United States Navy

Application April 10, 1943, Serial No. 482,588

5 Claims. (Cl. 201—51)

(Granted under the act of March 3, 1883, as
amended April 30, 1928; 370 O. G. 757)

Our invention relates in general to voltage regulators for generators and in particular to such regulators which incorporate a variable resistor connected in series with the generator field winding, the resistor being controlled by means of a contact arm connected to the movable core of a solenoid energized by the terminal voltage of the generator.

Regulators of this particular type comprising a solenoid operated rheostat are well known but it is believed that the improved construction offered by the present application constitutes a meritorious advance in the art.

The general object of our invention therefore is to provide an improved voltage regulator of the class described which will maintain the terminal voltage of a generator at a constant value.

A more specific object is to provide novel means for adjusting the connections between the reciprocally movable core of the solenoid and the pivotally movable contact arm of the rheostat so that the amount of resistance cut into and out of the generator field circuit per unit length of travel of the core may be varied to suit different conditions of calibration for the regulator.

These and other objects of our invention will become more apparent from the detailed description to follow and from the accompanying drawing, the single figure of which is an elevational view of a preferred embodiment of the invention with the housing cover removed and certain parts shown in section. Electrical connections between the regulator and a shunt type generator are shown schematically.

Referring now to the drawing, a housing 2 for the regulator is shown with the cover removed. A solenoid 3 having a winding 4, a winding support 5 and a soft iron core on plunger 6 is provided, the support 5 being secured by any suitable means to one wall of housing 2. Resilient means consisting of a plurality of serially connected "button" or "disc" type springs 7 are disposed within the central opening through the solenoid 3. This type of spring is preferred because it has a more linear pressure characteristic than a coil spring. The topmost spring bears against the bottom of the core 6 and a bearing plate 8 is provided on the base of the lowermost spring. An adjusting screw 9 having a knurled head 10 threads through a collar 11 secured to the wall of the housing 2 and the end of the screw 9 bears against the underside of plate 8. Screw 9 may be locked in any position by means of a lock nut 12. The static or no-load voltage regulation is determined by the position of screw 9, which, acting through the springs 7, sets the average operating point for the apparatus.

A plurality of spaced pins 13 secured to, and upstanding from, one wall of housing 2 are provided to carry a plate member 14 which may be 60

made of any suitable electrically insulating material. The pins 13 project through complementary spaced, elongated slots 15 provided in plate 14 and transverse movement of plate 14 is provided by a screw 16. Screw 16 having a knurled head 17 threads into a recess portion 18 provided in one end of plate 14. Thus as screw 16 is rotated (but cannot move along its axis because of the retaining collars 19, 20), plate 14 will be moved transversely.

Mounted upon the plate 14 is a slide wire rheostat 21 consisting of a flat wound curved wire resistor 22 and a carbon brush 23, the latter being carried in a recess 24 provided in an arm member 25 which is pivotally mounted on pin 26 upstanding from plate 14. The arm 25 is also made of suitable electrically insulating material and a spring 27 is provided between one end of brush 23 and the bottom of recess 24 to urge brush 23 into good electrical contact with the resistor 22.

Arm 25 is provided with a transversely arranged slotted portion 28, and a pin 29 which passes through slot 28 and is secured to the top end 25 of core 6 provides pivotal connecting means between core 6 and arm 25.

To connect the regulator in circuit, the resistor 22 is connected in series with the field winding 30 of a generator by conductors 31 and 32. Conductor 31 is connected between one side of the generator field winding 30 and brush 23 while conductor 32 is connected between one side of the generator armature 33 and one end of the resistor 22.

Conductors 34 and 35 take power outwardly from the output terminals of the generator to supply its load and the solenoid winding 3 is connected by conductors 36 and 37 so as to be energized by the terminal voltage of the generator.

By turning the screw 16, which moves plate 14 and hence arm 25 transversely, the distance x between pivot pins 26 and 29 is varied, thus varying the ratio of movement of arm 25 to core 6, and determining the amount of resistance which is added to or subtracted from the generator field circuit for a given displacement of the core 6.

Operation

The regulator operates in the following manner:

Assuming that for a given generator terminal voltage, the core 6 occupies the position shown in the drawing. If the terminal voltage of the generator should now tend to decrease which tendency might be caused by an increase in output current, or decrease in field strength or decrease in speed, the current flow through the coil 2 will decrease and will likewise decrease the pull exerted thereby on core 6. As the pull on core 6 lessens, the restoring force in springs

7 push core 6, arm 25 and brush 23 upwardly thereby decreasing the amount of resistance in series with the generator field winding 30. This allows more current to flow through the field winding increasing the field flux and hence the voltage output of the generator is also increased.

Conversely if the terminal voltage of the generator should for any reason tend to increase, current flow in coil 3 and the pull exerted on core 6 will likewise increase. This pulls core 6 further within the core opening and thereby increases the resistance in series with the generator field winding 30. Current flow through winding 30 is thereby decreased which decreases the generator field flux and hence the terminal voltage of the generator is also decreased.

Thus it will be evident that any tendency towards a decrease in terminal voltage of the generator will be offset by an increase in generated voltage while any tendency towards an increase in terminal voltage of the generator will be offset by a decrease in generated voltage. The net result of this is that substantially a constant terminal voltage on the generator is maintained irrespective of any condition which might tend to change this voltage.

In conclusion, we wish it to be understood that the particular construction which has been described represents only one embodiment of the invention and that various changes therein may occur to those skilled in the art without departing from the spirit and scope of the invention as defined in the appended claims.

For example, it may be desirable, in some instances, to replace the curved resistor 22 with a plurality of arcuately arranged contact members which are wiped by the brush 23, resistance coils of any desired resistance values being connected between adjacent contact members so that as the brush 23 passes from one contact to another, the resistance coils are cut in and out of the field circuit. Such a contact arrangement per se is shown in U. S. Patent No. 589,073.

The invention described herein may be manufactured and used by or for the Government of the United States of America for governmental purposes without the payment of any royalties thereon or therefor.

We claim:

1. In a regulator for a generator a solenoid including a movable core, a rheostat comprising a movable contact arm and a resistor, said resistor being adapted to be connected in the field circuit of said generator, means for connecting said movable core with said movable contact arm, and means for modifying said connecting means whereby changes in ratio of movement of said contact arm to movement of said core may be effected.

2. In a regulator for a generator, a solenoid including a movable core, a rheostat comprising a contact arm and a resistor, said resistor being adapted to be connected in circuit relation with

the field winding of said generator, first pivot means about which said contact arm is movable to vary the resistance of said resistor, second pivot means connecting said core to said contact arm, and means for varying the distance between said first and second pivot means to thereby vary the ratio of movement of said contact arm to movement of said core.

3. In a regulator for a generator, a solenoid 10 adapted to be energized by the voltage produced by said generator and including a movable core, a rheostat comprising a support plate, a curved resistor mounted on said support plate, an arm member having contact means at one end thereof to engage said resistor and first pivot means at the opposite end thereof for pivotally mounting said arm member on said support plate, second pivot means connecting said core to said arm member intermediate said first pivot means and said contact means, and means for moving said support plate and arm member carried thereby transversely of the axis of movement of said core to vary the distance between said first and second pivot means thereby varying the ratio of movement of said arm member to movement of said core.

4. In a regulator for a generator, a solenoid including a movable core, a rheostat adapted to be connected in the field circuit of said generator, 30 said rheostat including a support plate, a curved resistor disposed on said plate, a resistor contact arm having a slotted portion and first pivot pin means for pivotally mounting said contact arm on said support plate, said arm extending substantially normal to the axis of movement of said core, second pivot means comprising a pin secured to the end of said core and extending into the slotted portion of said contact arm for connecting said contact arm to said core, and means 35 for moving said support plate, contact arm and resistor carried thereby relative to said core to effect a change in the distance between said first and second pivot pin means and hence a change in the ratio of movement of said contact arm to movement of said core.

5. In a regulator for a generator, a rheostat including an arm and resistor, said rheostat being adapted to be connected in circuit relation with the field winding of said generator, a solenoid 40 adapted to be electrically connected with the terminals and generator, said solenoid including a movable core, resilient means opposing movement of said core, said resilient means comprising one or more disk type springs, first pivot means about which said rheostat arm is movable to vary the resistance of said resistor, second pivot means connecting said core to said rheostat arm, and means for varying the distance between said first and second pivot means to thereby vary the ratio of movement of said rheostat arm to movement of said core.
